UNITED STATES PATENT OFFICE

HOWARD D. TAYLOR, OF NEW YORK, N. Y., ASSIGNOR TO FLEXIBLE TRUCK CORPORATION, OF READING, PENNSYLVANIA, A CORPORATION OF DELAWARE

CAR TRUCK BOLSTER

Application filed February 14, 1930. Serial No. 423,255.

The invention relates to bolsters for railway car trucks and seeks to provide an improved construction particularly adapted for use in trucks, such as set forth in prior Letters Patent of the United States Nos. 1,594,576 and 1,594,645, issued to me August 3, 1926.

The invention consists in the features of improvement hereinafter set forth, illustrated in the accompanying drawings and more particularly pointed out in the appended claims.

In the drawings:

Fig. 1 is a side elevation of the truck with the improved bolster applied thereto.

Fig. 2 is a view of the bolster partly in plan and partly in horizontal section on the line 2—2 of Fig. 3.

Fig. 3 is a view of the bolster partly in side elevation and partly in vertical section on the line 3—3 of Fig. 2.

Fig. 4 is an end view, and

Figs. 5 and 6 are transverse sections on the lines 5—5 and 6—6 of Figs. 2 and 3.

As set forth in the prior patents referred to, the truck side frames *a* are provided with large bearing openings at their central portions within which carrier rings *b* are journaled, the rings being provided with openings to receive the ends of the bolster *c* and spring plank *d*, and the interposed springs *e*. The rings on opposite sides of the truck are interlocked with the bolster ends by means of column guide lugs 10 at opposite sides of each ring and pairs of co-operating lugs 12 on opposite sides of each end of the bolster. Each ring is also interlocked with the side frame in which it is journaled by means of keys 13, but in a manner permitting the limited rocking movement of the side frames.

The bolster is preferably formed of a single integral casting and comprises top and bottom walls 14 and 15 and opposite side walls 16. The end portions of the bolster which extend within the upper portions of the openings of the carrier rings *b* are of contracted height, and the corresponding portions 17 of the top wall of the bolster are arched in section, while the bottom walls 15 are inclined upwardly from the central por-

tion of the bolster and terminate in substantially horizontal spring-engaging portions or seats 18.

To stiffen the bolster without contracting the space required for the bolster springs, 55 the side walls 16 extend downwardly below the inclined portions of the bottom wall and below the spring seats and provide strengthening flanges 19, and the latter are connected at the inner ends of the spring seats by transverse depending flanges 20. The portions of the top wall adjacent the arched ends 17 thereof are preferably thickened and provided with horizontal upper surfaces to provide seats 21 for the side bearings. To further 60 stiffen the end portions of the bolster, the portions 17 and 21 of the top wall 14 are connected to the adjacent parts of the bottom wall by vertically disposed stiffening ribs or walls 22 extending longitudinally of the bolster midway between the side walls thereof and which, in the form shown, are provided with core openings. Also, in the form shown, the flanges 19 and the spring seats 18 are connected by stiffening fillets 23 which are cut 65 away at intervals to accommodate the bolster springs. Preferably, also, the extreme ends of the arched portions 17 and the spring seats 18 are provided with transverse stiffening beads 24 and 25. The top wall is provided with the usual central bearing portion 70 26 and the central portions of the top and bottom walls below the bearing are connected by vertical walls 27 which are strengthened by bracing ribs 28.

Between the center of the bolster and the end portions 17 of the top wall, the top, bottom and side walls form a structure which is substantially rectangular in cross-section. That is to say, except at its arched ends, the 75 top wall is flat and horizontal in transverse direction, and except opposite the arched end portions 17, the side walls extend throughout the height of the bolster and merge into the opposite edges of the top wall substantially at right angles. This rectangular box section forms a bolster of stout construction, particularly at the central and side bearing portions thereof. To avoid abrupt angular portions between the flat and arched parts of 80 100

the top wall, the latter, at points intermediate the arched ends 17 and the side bearing seats 21, is provided with triangular sections 29 which are convexly curved in transverse direction and concavely curved longitudinally of the bolster and merge into the arched end portions 17 of the top wall. It is noted that the upper portion of the arched end 17 and the side bearing seats 21 are in substantial alignment with one another and with the other portions of the top wall of the bolster, so that there are no abrupt angular portions or offsets in the upper wall or compression member of the bolster.

13 Intermediate the center and end portions of the bolster, the top and bottom walls are provided with core openings 30 and the walls about these openings are stiffened, preferably by thickening the central portions thereof, as shown in Fig. 6.

Changes may be made in the details shown and described without departure from the scope of the appended claims.

I claim as my invention:

1. A car-truck bolster comprising top, bottom, and opposite side walls, the top wall having arched end portions, and said walls otherwise forming a structure substantially rectangular in cross section, substantially as described.

2. A cast truck bolster having top, bottom and opposite side walls, the top wall having arched end sections but otherwise and throughout the greater part of its length merging into the upper edges of said side walls substantially at right angles thereto and the upper portions of the arched ends being in substantial alignment with the other portions of the top wall, substantially as described.

3. A cast truck bolster having contracted ends and comprising a top wall having arched ends, a bottom wall inclined upwardly from the center of the bolster and terminating in spring seats, and opposite vertical side walls of contracted height opposite said arched ends and spring seats but otherwise extending substantially throughout the height of the bolster, substantially as described.

4. A cast truck bolster having contracted ends and comprising a top wall having arched ends, a bottom wall inclined upwardly from the center of the bolster and terminating in spring seats, and opposite vertical side walls of contracted height opposite said arched ends and spring seats but otherwise extending substantially throughout the height of the bolster, and the side walls forming stiffening flanges depending below the inclined and the spring seat portions of the bottom wall, substantially as described.

5. A cast truck bolster comprising a top wall having flat side-bearing seats adjacent its ends and being substantially horizontal in

section at and between said seats and of arched section at its ends outside of said seats, vertical side walls depending from the edges of the top wall and a bottom wall disposed above the lower edges of said side walls throughout the greater portion of its length and terminating in spring seats below the arched ends of the top wall, and vertical, longitudinal, stiffening walls extending between the arched ends and seats of the top wall and the adjacent portions of the bottom wall, substantially as described. 70 75

6. A cast truck bolster comprising top, bottom and opposite vertical side walls, the top wall having side-bearing seats and a substantially flat upper surface at and between said seats and being arched in section at its ends outside of said seats and the upper portions of the arched ends and said seats being in substantial alignment with the other portions of the top wall, substantially as described. 80 85

7. A cast truck bolster comprising top, bottom and opposite vertical side walls, the top wall having side-bearing seats and a substantially flat upper surface at and between said seats and being arched in section at its ends outside of said seats, the upper portions of the arched ends and said seats being in substantial alignment with the other portions of the top wall, and said top wall having curved portions at the outer edges of the seats that merge into the arched ends, substantially as described. 90 95

8. A cast truck bolster comprising top, bottom and side walls, the top wall having side-bearing seats and being substantially horizontal throughout the width of the bolster at and between said seats and arched in section at its ends outside of said seats, and the top wall having triangular curved portions at the outer edges of the seats that merge into the arched end sections, substantially as described. 100 105

9. A cast truck bolster comprising top, bottom and opposite vertical side walls, the top wall having side-bearing seats and arched ends outside of said seats, and said vertical side walls, at and between said seats, extending substantially throughout the height of the bolster, substantially as described. 110

10. A cast truck bolster comprising top, bottom and opposite vertical side walls, the top wall having side-bearing seats and arched ends outside of said seats, the bottom wall being inclined upwardly from the center of the bolster and terminating in spring seats, and said vertical side walls extending below the inclined portions and the spring seats of the bottom wall, and extending substantially throughout the height of the bolster at and between the side-bearing seats, substantially as described. 115 120 125
